DESIGN FOR A COMBINED CLOTHESPIN AND HANGER OR SIMILAR ARTICLE

Sidney R. Pine, Maplewood, N. J.

Application October 26, 1944, Serial No. 115,993

Term of patent 14 years

(Cl. D17—6)

To all whom it may concern:

Be it known that I, Sidney R. Pine, a citizen of the United States and a resident of Maplewood, in the county of Essex and State of New Jersey, have invented a new, original, and ornamental Design for a Combined Clothespin and Hanger or Similar Article, of which the following is a specification, reference being had to the accompanying drawing, forming part thereof.

I claim:

The ornamental design for a combined clothespin and hanger or similar article, as shown.

SIDNEY R. PINE.
